HEEL COVER TRIMMING MACHINE

Milton H. Ballard, Beverly, Earl A. Bessom, Marblehead, and Norwood H. Knowlton, Rockport, Mass., assignors to United Shoe Machinery Corporation, Paterson, N. J., a corporation of New Jersey

Application June 13, 1932, Serial No. 616,928

26 Claims. (Cl. 12—42)

This invention relates to machines for use in the manufacture of shoes and is illustrated as embodied in a machine for skiving the projecting marginal portions of covers attached to heels.

- 5 In the manufacture of shoes it is customary to cover heels such, for example, as wood heels of women's shoes prior to attaching the heels to their respective shoes. In covering such heels a cover which consists of a single piece of covering material, is adhesively secured to the rear and the side surfaces of the heel, the cover being larger than the surfaces so that its marginal portions project beyond the breast and the attaching faces of the heel. After the cover has 10 been cemented to the rear and side surfaces of the heel the projecting marginal portions of the cover are inturned upon and are secured to the breast and the attaching faces of the heel respectively. In order that the marginal portions 15 of the cover may conform to and form a smooth surface with the breast of the heel so that such portions will not be noticeable when the breast cover or flap has been cemented to the breast of the heel it is customary to trim material from the outside surface of each of the inturned marginal portions by skiving cut starting just within the breast edge and terminating in a feather edge. The marginal portion of the cover inturned upon the attaching face of the heel is 20 also skived in like manner in order to insure that the uncovered central part of the attaching face of the heel may readily be forced into engagement with the convex heel seat during the heel attaching operation. When the marginal portions of the cover are skived as above described 25 rough outer surfaces to which the breast flap may be effectively cemented or by which the heel may be attached more securely to the shoe upper are formed.
- 30 It is an object of this invention to provide a machine which may be used quickly and effectively to skive the projecting marginal portions of covers attached to and projecting beyond heels to a predetermined width prior to cementing such portions to the heel.
- 35

With the above object in view and in accordance with a feature of this invention the illustrated machine is provided with a cutter, mechanism positioned adjacent to the cutter and constructed and arranged to feed a projecting marginal portion of a cover attached to a heel against the cutter, and means illustrated as gages for guiding the heel and the projecting marginal portion of its cover relatively to said mechanism and past the cutter to skive the marginal portion. In

the illustrated construction the projecting marginal portion of the cover is fed by a pair of driven feed rolls against the cutter, which is of the rotary disk type and has its cutting edges disposed diagonally across an opening formed between the rolls, one of the rolls being yieldably movable under pressure of the cover toward and away from the other for varying the width of the opening in accordance with the thickness of the cover upon which the machine is operating. The heel may be so positioned and guided by the gages relatively to the feed rolls that the projecting marginal portion of its cover is trimmed substantially to the width of the feed rolls by a skiving cut which removes material from the grain side of the marginal portion and starts adjacent to the heel and terminates in a feather edge.

The illustrated gages comprise an elongated gage overlapping the cutter and arranged for engagement with a covered face of the heel and a convex end surface of the lower roll shaped and arranged to engage the face of the heel beyond which the marginal portion of the cover projects. The machine is also provided with a swinging gage arranged for engagement with the heel face 25 which engages the convex end surface of the roll and adapted to cooperate with the elongated gage in guiding the heel and the projecting marginal portion of its cover relatively to the feed rolls until the convex end surface of the lower feed roll 30 becomes effective as a guiding surface. Such an arrangement enables the operator accurately and quickly to move the heel into engagement with the convex face of the feed roll, which is hidden from view of the operator by the marginal portion of the covering to be trimmed, without having to feel for such face.

It is desirable to trim the projecting marginal portions of the cover to a constant width although the cover material may vary in thickness and with this in view the rotary disk cutter is angularly adjustable in response to the movement of one of the feed rolls relatively to the other, such movement being caused by variations in the thickness of the cover being skived.

In order to support the part of the projecting marginal portion of the cover which extends beyond the rolls as the cover is fed against the cutter, as well as to insure that the marginal portion is skived to a feather edge terminating at 50 the inner end of the feed rolls, the illustrated machine in accordance with a further feature of the invention is provided with a support positioned adjacent to the opening formed between the rolls and constructed and arranged to bend 55

the marginal portion across the cutting edge of the cutter. The support has the form of a freely rotatable disk which overrides the rotary disk cutter and also serves as a chip disposing member 5 to prevent portions trimmed from the cover and coated with cement from being deposited upon the cutter.

In the drawings,

Figs. 1, 2 and 3 are front, side and plan elevational views respectively of the illustrated machine;

Fig. 4 is a perspective view showing a heel the marginal portions of the cover of which are being skived to a predetermined width in the illustrated machine;

Fig. 5 is a detail view illustrating the position of a heel and a cover attached thereto, with reference to cover feeding and skiving instrumentalities of the illustrated machine during the cover skiving operation;

Fig. 6 is a perspective view of a heel the projecting marginal portions of the cover of which have been skived to a predetermined width in the illustrated machine.

The illustrated machine is described with reference to the skiving of the projecting marginal portions 20 of covers 22 cemented to wood heels 24. In covering such heels the cover, which may be made of leather or of any other suitable material, is applied to the side and to the rear faces of the heel, the cover being larger than such faces and extending beyond the attaching and the breast faces 26, 28 respectively of the heel. In covering heels it is customary to turn the projecting portions 20 of the cover upon the breast and the attaching faces respectively of the heel and then to skive to a feather edge, for reasons above explained, the marginal portions of the cover.

In order to skive the projecting marginal portions 20 of the cover the illustrated machine is provided with a rotary disk cutter or knife 30, upper and lower positively rotated feed rolls 32, 34, respectively constructed to force the projecting marginal portion 20 of the cover attached to the heel against the cutter 30, and a gage 36 arranged to engage the covered face of the heel and to cooperate with a convex end portion or heel engaging face 37 of the lower roll 34 to position the heel and the projecting marginal portion of its cover relatively to the feed rolls and to the cutter. The above mechanism, together with other work-guiding elements, will later be described in detail.

The operative parts of the machine are supported upon a main frame 38, which may be bolted to a work table, not shown, and includes a standard 40 to which an electric motor 46 may be secured by bolts 42. Power is supplied to the feed rolls 32, 34, the rotary disk cutter 30, and a rotary grinder 48 for sharpening the cutter through a vertically disposed counter shaft 50 which is journaled in upper and lower bearings 52 supported by the main frame and is driven through a belt 54 by a pulley 56 mounted upon a shaft of the motor 46.

The feed rolls 32, 34 may be secured to or may be formed integral with upper and lower shafts 58, 60, respectively, which are rotatably mounted and are positively driven, the upper shaft 58 being journaled in bearings 62, 64 (Fig. 2) rigidly secured to an adjustable portion 66 (Fig. 2) of the main frame and the lower shaft 60 being journaled in front and rear housings 68, 70, respectively, both of which are movable relatively

to the adjustable portion 66 of the main frame to cause the lower roll 34 to swing toward and away from the upper roll 32 for reasons which will be explained later.

The feed rolls 32, 34 may be adjusted as a unit toward and away from the cutter 30, together with the adjustable portion 66 of the main frame, since such portion is mounted for angular adjustment about a pin 72 (Fig. 2) passing through the adjustable portion 66 and secured to a stationary part of the main frame. Adjustment of the portion 66 relatively to the stationary main frame may be readily effected by releasing a clamp screw 74, which is in threaded relation with the adjustable portion 66 of the main frame and passes through an arcuate slot 76 in the stationary part, and by then turning a screw 78 rotatably mounted in the stationary part of the main frame and in threaded relation with a lug 80 (Fig. 3) pivotally attached to the adjustable portion 66.

In order to provide for feeding covers of varying thickness against the rotary disk cutter 30 the lower roll 34, which when the machine is inoperative is normally spaced from the upper roll 32 by a distance slightly less than the minimum thickness of the covers to be operated upon, is yieldable away from the upper roll 32 under pressure of the cover during the skiving operation. This is effected by mounting the front housing 88 for vertical movement in a slideway 82 of a pedestal 84 carried by the adjustable portion 66 of the main frame and by rotatably supporting the rear housing 70 from a cylindrical projection 86 (Fig. 3) which is also mounted in the adjustable portion 66 of the main frame. The shafts 58 and 60 which, it will be noted, are inclined to each other to facilitate the feeding of work to the machine, are driven from a vertically disposed shaft 38 mounted for rotation in spaced bearings 90 (Fig. 2) of an upstanding bracket 32 of the adjustable portion 66 of the main frame. A pair of bevel gears 94 and 96 constructed and arranged to mesh with gears 98, 100, respectively, mounted upon the vertical shaft 38, are keyed 45 to the shafts 58 and 60 respectively, the shaft 98 being driven by a pulley 102 which receives power from a belt 104 in driving relation with a pulley 106 of the counter shaft 50.

As above stated, in trimming the projecting marginal portions 20 of covers attached to heels it is desirable that the covers be skived to a uniform width and that the skive shall start at portions slightly removed from the breast edges 103 (Fig. 6) or the rim 110 of the heel over which the covering is turned in order that the skiving cut may not be visible in the finished shoe. With this in view the convex face 37 of the feed roll 34 and the gage 36 are constructed and arranged to position the edge beyond which the projecting marginal portion 20 extends slightly away from the cover-engaging faces of the feed rolls 32, 34.

It will be noted that the cover-engaging faces of the feed rolls 32, 34 are of equal length and of frusto-conical shape, the width of the skived marginal portion being equal to the length of the faces of the feed rolls since the cutting edge 112 of the rotary disk cutter 30 which is positioned adjacent to the openings formed between the rolls 32, 34 extends from an upper outer edge 114 to a lower inner edge 116 (Fig. 5) of the opening. By providing feed rolls 32, 34 of frusto-conical shape the inner portions of the rolls travel slightly faster than the other portions of the rolls and tend to pull the heel into engagement with the

convex surface 37 and also tend to iron out any wrinkles formed in the projecting marginal portion 28 of the cover. The feed rolls 32, 34, however, if desirable, may be cylindrical or of various other shapes according to the work being operated upon in the machine.

In order that the cutting edge 112 of the cutter 30 may extend from the upper outer edge 114 to the lower inner edge 116 of the opening as the roll 34 is moved toward and away from the roll 32 by varying thicknesses of covering material being skived, the rotary disk cutter 30 is mounted for adjustment about the axis of a shaft 118 (Fig. 1) an extension of which axis extends through the upper outer edge 114. The adjustment of the cutter 30 about the shaft 118 is automatically effected by pivotally connecting an angular offset arm 120 (Fig. 2), which is journaled in the pedestal 84 at 122, to the front housing 68. The arm 120 at its upper end carries an adjustable screw 124 which engages a face 126 of a curved arm 128 mounted upon a pin 130 which is pivotally supported in a bearing housing 132. The forward end of the arm 128 is bifurcated and includes a roll 134 extending from a cutter carrying bracket 136 mounted upon the shaft 118.

The cutter carrying bracket 136 is normally held in a raised position by a spring 138 the lower end of which is attached to a screw secured to the bracket 136 and the upper end of which engages a shaft 140 secured to the frame of the machine. The lower feed roll 34 is normally urged toward the feed roll 32 by the tension spring 139 operating through the above-described mechanism, the feed rolls being normally spaced at a minimum distance apart, such distance, as above stated, being slightly less than the minimum thickness of heel covers to be skived. Movement of the roll 34 toward the roll 32 is limited by a screw 142 (Fig. 2) which is adjustable relatively to the machine frame to vary the extent of movement of the roll 34 under the action of spring 138 toward the feed roll 32. The angularity of the cutting edge 112 of the cutter with respect to the opening may be initially varied by turning the screw 124 thereby adjusting the cutter 30 about the axis of the shaft 118.

The cutter 30 may be raised or lowered relatively to the cutter-carrying bracket 136 by moving a shaft 144 secured to the cutter 30 lengthwise of its axis of rotation through mechanism such as is used in various other machines of the Amazeen type and which will now be described briefly. The shaft 144 is rotatably mounted in upper and lower bearings 146 and 148, respectively, (Fig. 1) rigidly connected to the bracket 136 and is provided at its central portion with a collar 150 shaped for positioning within a bifurcated portion of a block 152 having another bifurcated portion constructed to include a collar 154 secured to a rod 156 the lower end of which is in threaded relation with the lower bearing 148. The shaft 144 may thus be raised or lowered by turning the rod 156. The cutter 30 is rotated through a belt 158 which is in driving relation with a small pulley 160 keyed to the shaft 144 and receiving its power from a large pulley 162 mounted upon the countershaft 50.

The cutter 30 may be conveniently sharpened by the rotary grinder 48 mounted upon a shaft 164 (Fig. 1) which is supported for lengthwise adjustment in a U-shaped extension 166 of the cutter-carrying bracket 136. The grinder 48 is normally held away from the cutter 30 but may be moved into and out of engagement with the

cutter by turning a knurled collar 168. The shaft 164 has secured to it a pulley 170 for receiving a belt 172 which passes around a pulley 174 (Fig. 1) mounted upon the countershaft 50. The belt 172 may be tightened to drive the pulley 170 by a belt tensioning pulley 176 mounted for swinging movement upon an arm 178 which is mounted upon a shaft 180 carried by the cutter carrying bracket 136.

The arm 178 is provided with a spring-pressed plunger pin 182 (Fig. 1) constructed and arranged to engage one of a series of serrations 183 of the cutter carrying bracket 136 to hold the tensioning pulley 176 against the belt 172 to cause the same to be tensioned.

In order to assist the operator initially to position the heel 24 and the projecting margin 28 of its covering relatively to the feed rolls 32, 34 and to the cutter 28 the illustrated machine is provided with a swinging gage 184 which is pivotally mounted on a pin 186 secured to the main frame and is normally urged to its outward position away from the rolls by a spring 188 (Fig. 1). The front face 190 (Fig. 4) of the gage 184 is substantially in alignment with the convex face 37 of the roll 34 and is constructed and arranged to cooperate with the gage 36 initially to position the heel after which the gage 184 and the heel are swung together toward the feed rolls. Such an arrangement insures that when the attaching surface of the heel, for example, which is hidden from the view of the operator by the projecting marginal portion 28 of the cover is moved to the left (Fig. 1) the leading portion of such surface may be moved into contact with the heel engaging face 37 of the roll 34 without the operator having to feel for the face 37.

In order to insure that the skiving cut will terminate at the lower inner edge 116 (Fig. 5) of the opening formed between the feed rolls 32, 34 and also to insure that the end of the skive terminates in a clean cut feather edge, the part 192 (Fig. 5) of the projecting portion 28 is engaged by a cover support or rotatable disk 194 which is located adjacent to the inner end of the opening and overlaps the rotary disk cutter 30. It will be noted that the disk 194, which is rotatably secured to a shaft 196 (Fig. 4) supported in a bushing 198 in threaded relation with a housing 200, causes the part 192 of the cover to be bent across the cutting edge 112 of the cutter 30 as the cover is fed against the same.

The rotatable disk 194 may be adjusted heightwise of the opening formed between the feed rolls 32, 34 by turning the bushing 198 in the housing 200. The inner surface of the cover is coated with cement and as the heel and its projecting cover are moved past the cutter 30, the rotary disk 194 also serves as a chip ejector and insures that the chip removed from the cover shall not come into contact with and stick to the cutter.

The gage 36 extends under the rotary disk cutter 30 to insure that the side cover shall not come into contact with the cutter. In order to safeguard the fingers of the operator the machine is provided with a guard 202 which extends around a substantial portion of the cutting edge 112 of the cutter 30.

In order to skive the projecting marginal portions 28 of the heel cover to a predetermined width 70 the operator after making the proper adjustments engages the covered face of the heel with the gage 36 (Fig. 4) and moves the heel so that its attaching surface rests against the face 190 of the swinging gage 184. The heel and the gage 75

184 are then moved toward the rolls 32, 34, the projecting marginal portion 20 of the cutter being fed between the rolls and the attaching face of the heel being moved into contact with 5 the convex face 37 of the roll 34. The gage 36 and the convex face 37 are then utilized to guide the heel and the projecting marginal portion 20 relatively to the feed rolls 32, 34 and to the cutter 39 as the rolls feed the projecting marginal portion 10 against the cutter to skive the marginal portion to a predetermined width.

Having thus described our invention, what we claim as new and desire to secure by Letters Patent of the United States is:

15 1. In a trimming machine, a cutter, mechanism positioned adjacent to the cutter and constructed and arranged to feed a projecting marginal portion of a cover attached to a heel against the cutter, and means to guide the heel and the projecting portion of the cover relatively to said mechanism and past the cutter to skive said projecting marginal portion.

20 2. In a trimming machine, a cutter, mechanism positioned adjacent to the cutter and constructed and arranged to feed a projecting marginal portion of a cover attached to a heel against the cutter, and gages to guide the heel and the projecting portion of the cover relatively to said mechanism and past the cutter to skive said projecting marginal portion.

25 3. A trimming machine having, in combination, a cutter, members constructed and arranged to feed a projecting marginal portion of a cover attached to a face of a heel against the cutter, and a gage to engage the covered face of the heel, one of said feed members being constructed and arranged to engage another face of the heel and to cooperate with the gage to position the heel and the projecting marginal portion relatively to the members as the members feed the projecting portion 30 against the cutter.

40 4. A trimming machine having, in combination, feed members constructed and arranged to engage opposite sides respectively of a projecting marginal portion of a cover secured to a face of a heel, a cutter positioned adjacent to the feed members, and gages to engage angularly disposed faces of the heel to position the same and the projecting marginal portion of its cover relatively to the members in such manner that, as the members feed said portion against the cutter, the projecting marginal portion will be skived to a width equal to the length of the cover-engaging faces of the feed members.

45 5. In a trimming machine, a cutter, a member and a feed roll constructed and arranged to engage opposite sides respectively of a marginal projecting portion of a cover secured to a heel and to force said portion against the cutter, an elongated gage positioned adjacent to an end 50 of the roll and extending transversely of the roll to engage the covered face of the heel, and a gage member having a surface positioned substantially in alinement with one end of the roll and constructed and arranged to engage a heel face which is angularly disposed to the covered face of the heel, said gage and said gage member being constructed and arranged to position the heel and the projecting marginal portion of the cover relatively to the cutter as the member and the feed roll force said portion against the cutter thereby to skive the projecting marginal portion.

55 6. In a trimming machine, a cutter, a pair of rolls to feed the projecting marginal portion of a cover attached to a face of a heel against the

cutter, one of said rolls having an end surface constructed to engage a heel face above which the marginal portion of the cover projects, a gage to engage the covered face of the heel, and a member movable transversely of the axis of rotation of the rolls, said member having a surface shaped and arranged to engage said first-mentioned face of the heel for locating the heel relatively to said end surface of the feed roll. 5

7. In a trimming machine, a pair of feed rolls, a cutter constructed to skive a projecting portion of a cover attached to a face of a heel and forced by the feed rolls against the cutter, and a gage positioned at one end of the rolls and overlapping the cutter to engage the covered face of the heel 10 and to cooperate with one of the feed rolls to position the projecting portion relatively to the feed rolls and to the cutter. 15

8. In a trimming machine, a cutter, means for operating the cutter to produce a draw-cut, mechanism positioned adjacent to the cutter and constructed and arranged to feed a projecting marginal portion of a cover attached to a heel against the cutter, and gages to position and to guide the heel and its projecting cover relatively to said mechanism and past the cutter to cause the marginal portion projecting beyond the heel to be skived to a predetermined width. 20

9. In a trimming machine, a rotary disk cutter, rolls positioned adjacent to the cutter and constructed to feed a projecting marginal portion of a cover attached to a heel against the cutter, and gages to position and to guide the heel and its projecting cover relatively to the rolls and past the cutter to cause the marginal portion to be 30 skived to a predetermined width. 35

10. In a trimming machine, a rotary disk cutter, a pair of feed rolls, and a rotary chip-disposing member positioned at one end of the rolls and overlapping the cutter. 40

11. A trimming machine having, in combination, a cutter provided with an elongated cutting edge, a pair of rolls for feeding a flexible cover against the cutting edge, means for operating the cutter to cause the cutting edge to move lengthwise of itself thereby to trim the cover fed by said rolls, and a rotatable disk constructed and arranged to bend portions of the cover which project beyond the rolls across the cutting edge as the cover is fed against the cutter. 45

12. A trimming machine having, in combination, a cutter provided with an elongated cutting edge, a pair of rolls for feeding a flexible cover against said cutting edge, means for causing the cutting edge of the cutter to move lengthwise 55 of itself, one of said rolls being yieldingly movable away from the other, and mechanism controlled by movement of one of said rolls to adjust the cutter relatively to the rolls in accordance with the thickness of the cover being 60 trimmed.

13. A trimming machine having, in combination, a cutter, a pair of relatively movable feed rolls constructed and arranged to receive the projecting marginal portions of covers of varying 65 thicknesses attached to faces of heels and to force said portions against the cutter, and gages to engage a covered face of each heel and a face beyond which the cover of each heel projects to guide the projecting marginal portion of the 70 cover in predetermined relation to the feed rolls.

14. A trimming machine having, in combination, a pair of driven rolls relatively movable transversely of their axes toward and away from each other and forming an opening to receive ma- 75

5 terial of various thicknesses, a disk cutter having a cutting edge positioned adjacent to and extending diagonally across the opening formed between the rolls, and means responsive to the relative movement of the rolls in a direction transverse to their axes for angularly adjusting the cutter to insure that the cutting edge will maintain a constant relation with respect to the opening as the size of the opening is changed by varying thicknesses of material.

10 15. A trimming machine having, in combination, spaced feed members constructed and arranged to engage opposite sides respectively of a projecting marginal portion of a cover secured to a surface of a heel and mounted for relative movement toward and away from each other to accommodate covers of varying thicknesses, a cutter positioned adjacent to the feed members and extending diagonally of the space formed between the members, a gage to engage the covered surface of the heel, a gage to engage a face which is angularly disposed to the covered surface, and mechanism responsive to the relative movement of the feed members to adjust the cutter angularly relatively to the members to insure that, as the members force covers of varying thicknesses against the cutter, the cutter will be positioned to skive the projecting marginal portion of the cover to a length equal to that of the feed members.

20 25 30 35 16. In a trimming machine, a cutter, and a pair of frusto-conical rolls mounted for rotation about axes one of which is inclined to the other and constructed and arranged to feed the projecting marginal portion of a cover secured to a heel against the cutter, one of said rolls having a convex end surface to engage the heel to guide said projecting marginal portion between the rolls.

40 45 50 55 17. A trimming machine having, in combination, a cutter, a pair of frusto-conical rolls constructed and arranged to feed the projecting marginal portion of a cover attached to a heel against the cutter, one of said rolls having an end surface to engage one face of the heel, and a gage positioned adjacent to said end surface to engage the covered face of the heel and arranged to cooperate with the end surface of the roll to position the heel and the projecting portion of its cover relatively to the rolls.

60 65 70 75 18. In a trimming machine, a cutter, a pair of rolls spaced to form an opening and constructed and arranged to feed flexible sheet material against the cutter to skive said material, and a member positioned at one end of the opening and constructed and arranged to support a portion of the material extending beyond the rolls to insure that such portion is skived to a clean cut feather edge terminating at said end of the rolls.

19. A trimming machine having, in combination, a knife provided with an elongated cutting edge, a pair of feed rolls spaced from each other to form an opening between them and constructed and arranged to feed flexible material against said cutting edge, said cutting edge being positioned diagonally of and adjacent to the opening to cause the material fed against the knife to be trimmed by a beveling cut, and a rotary support positioned at one side of the opening and in overlapping relation to the cutting edge, said support being constructed and arranged to bend portions of the cover which project beyond the opening across the cutting edge of the knife there-

by to insure that the beveling cut terminates substantially at said one side of the opening.

20. In a trimming machine, a cutter having a lengthwise movable cutting edge, a pair of feed rolls constructed and arranged to force sheet material extending between and projecting laterally of the rolls against the cutter to skive said material to a width substantially equal to the width of the rolls, and a member positioned adjacent to the opposing portions of the rolls and at one end of the same constructed and arranged to support the marginal portion of the material extending beyond the rolls and to bend such portion across the cutter to insure that the cutter will form a clean cut feather edge terminating substantially at said end of the rolls.

roll toward and away from the other angularly to adjust the cutter relatively to the rolls.

26. A trimming machine having, in combination, a cutter provided with an elongated cutting edge, a pair of rolls for feeding a flexible cover in a predetermined path against said cutting edge, and means for causing the cutting edge of the cutter to move lengthwise of itself, one of

said rolls being yieldingly movable away from the other, and mechanism controlled by movement of one of said rolls constructed and arranged to tilt the cutter transversely of said path in accordance with the thickness of the cover being trimmed. 5
